UNITED STATES PATENT OFFICE.

DEWEY H. BITNEY, OF ALBION, MICHIGAN, ASSIGNOR TO UNION STEEL PRODUCTS COMPANY, OF ALBION, MICHIGAN.

COLLAPSIBLE RACK.

Application filed August 2, 1926. Serial No. 126,571.

The main object of this invention is to provide an improved wire rack for the display of merchandise in boxes or receptacles, such as cooky-caddies or the like, which is strong and rigid when erected and may be collapsed in a compact form for storage or shipment.

A further object is to provide an improved rack which is well adapted to support a plurality of boxes so that the contents are effectively displayed and the boxes may be individually opened without removing from the rack.

Objects pertaining to details and economies of my improvements will definitely appear from the detailed description to follow. The invention is clearly defined and pointed out in the claims.

A structure embodying the features of my invention is clearly illustrated in the accompanying drawing forming a part of this application, in which:

Fig. 1 is a front perspective view of a rack embodying the features of my invention in erected form with receptacles or boxes in position thereon.

Fig. 2 is a side elevation of the rack collapsed.

Fig. 3 is a fragmentary section through the upper part of the rack showing the relation of a receptacle to the shelf members or receptacle supports.

Fig. 4 is a fragmentary section showing the relation of a receptacle to the lower shelf members or supports.

Referring to the drawing, in the embodiment illustrated my improved rack comprises a pair of end members and a pair of side members pivotally connected to collapse upon each other longitudinally of the rack. The end members comprise uprights 1, 1 formed of wire of suitable gage, preferably of one piece, the wire being folded upon itself to provide a top cross member 2, the ends of the arms thus provided being folded into loops to provide feet 3 and the braces 4. Cross pieces 5 are disposed adjacent the lower ends of the end member uprights provided with eyes 6 at their ends.

The side members comprise uprights 7 also preferably formed of a single piece of wire or rod folded upon itself to provide the top cross piece 8, the ends of the uprights being bent inwardly and upwardly and dis-

posed in crossed relation providing diagonal braces 9.

The end members are also provided with cross pieces 10 and 11 projecting beyond the end uprights and terminating in eyes 6, the cross piece 10 having a central eye 12 while the cross piece 11 has a pair of eyes 13, these eyes and the eyes 6 being formed by coils in the cross pieces.

A pair of rod-like shelf members 14 are engaged in the eyes 13, these rods 14 having downturned ends engaging the eyes and providing a pivotal connection. A corresponding rod 15 is engaged in the eyes 12. The rods 14 are disposed in a plane below the top pieces 8 of the side members to coact therewith and support a receptacle 16 arranged as shown in Figs. 1 and 3.

A shelf supporting member 17 is arranged on the front side member in a plane above the rod 15 while a pair of shelf supporting members 18 are arranged on the rear side member in a plane above the rod 17, these members coacting with the member 15 in providing a shelf for the receptacle 16 which is arranged therein as shown in Fig. 4, one corner of the receptacle being engaged between the shelf members 18.

This provides an accurate locating means for the articles arranged on the lower shelf so that the receptacles on the shelves are presented in substantially the same position, that is, the two receptacles on the lower shelf would be properly aligned and also in proper position to make their contents readily accessible.

With the parts thus arranged the rack may be collapsed for shipment or storage, as shown in Fig. 2, very compactly, and when set up the structure is strong and rigid. Further, the structure is very economical to produce and is light in weight for shipment and handling.

I have illustrated my improvements in a small size rack only and have not attempted to illustrate the same in other embodiments which might require additional bracing. It is believed, however, that the disclosure made will enable those skilled in the art to embody or adapt my improvements as may be desired.

Having thus described my invention what I claim as new and desire to secure by Letters Patent is:

1. In a collapsible rack, the combination of end member uprights, upper and lower cross pieces disposed on said uprights with their ends projecting beyond the uprights 5 and having coils at their ends and intermediate the uprights, the upper cross pieces each having a pair of spaced eyes and the lower cross piece having centrally disposed eyes, rod-like shelf members engaged in said 10 intermediate eyes in said cross pieces, and side members comprising uprights engaging in said eyes at the ends of said cross pieces, and longitudinal members disposed on said uprights in planes above said shelf members 15 to cooperate therewith in forming a shelf, there being a pair of the said longitudinal members disposed on the rear side member above the lower shelf member and in spaced relation to each other to receive a corner of a receptacle resting on the bottom shelf member and on one of the front longitudinal 20 members. 50
2. In a collapsible rack, the combination of end member uprights, upper and lower cross pieces disposed on said uprights with their ends projecting beyond the uprights and having coils 25 at their ends and intermediate the uprights, the upper cross pieces each having a pair of spaced eyes and the lower cross piece having centrally disposed eyes, rod-like shelf members engaged in said intermediate eyes in said cross pieces, and side members comprising uprights engaging in 30 said eyes at the ends of said cross pieces, and longitudinal members disposed on said uprights in planes above said shelf members to cooperate therewith in forming a shelf. 60
3. In a collapsible rack, the combination of end member uprights, cross pieces disposed on said uprights with their ends projecting beyond the uprights and having coils 35 at their ends and intermediate the uprights, rod-like shelf members engaged in said intermediate eyes in said cross pieces, and side members comprising uprights engaging in 40 said eyes at the ends of said cross pieces, and longitudinal members disposed on said uprights in planes above said shelf members to cooperate therewith in forming a shelf. 70
4. In a collapsible rack, the combination of end members comprising uprights, cross pieces carried thereby and provided with eyes intermediate the uprights, side members pivotally connected to said end members, shelf members engaged in said eyes on 45 said end member cross pieces, and longitudinal members on said side members disposed in planes above and in coacting relation to said shelf members engaged with said eyes. 75
5. In a collapsible rack, the combination of end members, side members pivotally connected to said end members to permit the longitudinal collapsing of said side and end members, rod-like shelf members carried by 50 said side members, and coacting rod-like shelf members pivotally mounted on said end members in planes below the shelf members on said side members to coact therewith in providing an article supporting shelf. 80
6. In a collapsible rack, the combination of end members, side members pivotally connected to said end members to permit the longitudinal collapsing of said side and end members, rod-like shelf members carried by 55 said side members, and coacting rod-like shelf members pivotally mounted on said end members in planes below the shelf members on said side members to coact therewith in providing an article supporting shelf. 85
- In witness whereof I have hereunto set my hand.
- DEWEY H. BITNEY.
